ERASER DEVICE

Russell S. Henderson, Morristown, N. J., assignor
to Weldon Roberts Rubber Co., Newark, N. J., a
corporation of New Jersey

Application March 30, 1935, Serial No. 13,802

4 Claims. (Cl. 120—36)

This invention relates to improvements in erasers; and the invention has reference to a novel eraser device conveniently suited to the uses of typists, draftsmen, accountants and like workers, as well as for general use.

This invention has for its principal object to provide a novel eraser device whereby a plurality of bodies of erasive material are joined together in a unitary structure calculated to furnish a comparatively large mass better adapted to be firmly grasped and held by the hand in use, and yet wherein each body may be independently moved so as to expose the usable portions of its mass in position for use until such usable portions are entirely consumed.

The invention has for a further object to provide an eraser device of the kind referred to, in which the erasive bodies are of circular or approximately circular form and are joined together by an intermediate sustaining plate or link cooperative with outer plates to rotatably support and reinforce said bodies subject to exposure of all usable portions thereof in position for use and at the same time subject to selective use thereof, especially when the same possess different erasive characters.

Other objects of this invention, not at this time more particularly enumerated, will be understood from the following detailed description of the same.

An illustrative embodiment of the invention is shown in the accompanying drawing, in which:

Fig. 1 is a face view of an eraser device constructed in accordance with the invention; Fig. 2 is an edge elevation of the same; Fig. 3 is an end elevation of the same; Fig. 4 is a central longitudinal section through the same; and Fig. 5 is a face or plan view of the sustaining plate or link per se of the eraser device.

Similar characters of reference are employed in the above-described views, to indicate corresponding parts.

In preferred form the novel eraser device, according to this invention, comprises at least two bodies of erasive material, viz. the body 10 and the body 11. Each body is of disk-like form, and may be of any suitable peripheral shape, although preferably of circular or substantially circular shape. Each body is provided with a central opening 12. The bodies 10 and 11 are disposed flatwise in parallel planes, and preferably so that adjacent marginal portions thereof are in mutually overlapping relation. Interposed between said bodies 10 and 11, as thus disposed, is a sustaining or carrying plate 13 provided at its

respective ends with disk-like end-portions 14 and 15, each being of a diameter appreciably smaller than the diameters of the erasive bodies 10 and 11, and each having a central opening 16. The plate 13 may be made of any substantially rigid sheet material, but is preferably made of sheet metal. Provided for application on the outer sides of the respective bodies 10 and 11 are outer reinforcing or keeper disks 17 and 18, which also may be made of any suitable substantially rigid sheet material, but which are preferably made of sheet metal. The said outer disks 17 and 18 correspond in diameter to the diameters of the disk-like end-portions 14 and 15 of the carrying plate 13, being therefore of diameters appreciably smaller than the diameters of the erasive bodies 10 and 11 upon which they are applied. Said outer disks 17 and 18 each have a central opening 19.

In assembling the described elements of the novel eraser device, the erasive body 10 is centrally registered with and applied against the disk-like end-portion 14 at one side of the carrying plate 13, and the outer disk 17 is then applied centrally over the outer face of said erasive body 10, all whereby the openings 12, 16 and 19 of these parts are aligned together. To secure the parts in this assembled relation, a suitable central holding and pivoting eyelet or rivet 20 is passed through the aligned openings, and its opposite ends thereupon riveted over, as at 21, respectively against the end-portion 14 of the carrying plate 13 and the outer disk 17. In like manner, the erasive body 11 is centrally registered with and applied against the disk-like end-portion 15 at the opposite side of the carrying plate 13, and the outer disk 18 is then applied centrally over the outer face of the erasive body 11, all whereby the openings 12, 16 and 19 of these parts are aligned together. To secure these parts in such assembled relation, a suitable central holding and pivoting eyelet or rivet 22 is passed through said aligned openings, and its opposite ends thereupon riveted over, as at 23, respectively against the end-portion 15 of the carrying plate 13 and the outer disk 18.

In the eraser device thus constructed, the erasive bodies 10 and 11 are preferably disposed in somewhat overlapping relation, but each body is capable of rotation about its pivoting eyelet or rivet so that all parts of its usable marginal portions may be moved to freely projecting position at need until the entire usable mass of its erasive material is consumed.

The erasive bodies 10 and 11 may, if desired, be

respectively composed of material of different erasive characters or qualities. For example, the body 10 may comprise relatively hard abrasive material rendering the same usable for erasing ink marks, while the body 11 may comprise relatively soft abrasive material suitable for pencil mark erasure.

Each erasive body is firmly supported by the interlinking carrying plate so as to provide an assembly constituting a unitary structure which while being compact nevertheless furnishes, as a whole, a comparatively large mass well adapted to be firmly grasped by the fingers of the user, whereby the application of the part thereof desired to be utilized for an erasure operation is greatly facilitated, and all tendency to slipping, with risk of gouging or tearing the surface undergoing the erasure operation, is avoided.

From the above description it will be obvious that this invention provides a useful and convenient eraser device of neat and attractive appearance wherein all the advantages of the flat disk-like form of the well-known circular type-writer eraser is retained, with the added advantages of providing for a better grasp of the same by the user, and, if desired, the provision of different qualities of erasive material conveniently arranged for selective use.

Having thus described this invention, I claim:

1. In an eraser device, a support for a plurality of substantially circular eraser bodies comprising a carrier plate of a length less than the combined diameters of said bodies if laid edge to edge, and means adjacent to each end of said plate respectively projecting from opposite faces thereof for securing said bodies respectively upon opposite sides of said plate so that adjacent inner marginal portions of said bodies are in overlapping relation and outer marginal portions thereof extend freely beyond the extremities of said plate.

2. In an eraser device, a support for a plurality of substantially circular eraser bodies comprising a flat, relatively thin carrier plate of a length less than the combined diameters of said bodies if laid edge to edge, said plate having centrally

perforate approximately semi-circular end portions of a radius substantially less than that of the eraser bodies, retaining rivets carried by said perforate end portions, respectively projecting from opposite sides of said plate, on which the eraser bodies are mounted to lie respectively upon opposite sides of said plate so that adjacent inner marginal portions of said bodies are in overlapping relation and outer marginal portions extend freely beyond the peripheries of said plate end portions, and keeper discs secured by the outer ends of the said rivets in supporting relation to the outer faces of the eraser bodies so mounted. 5 10

3. In an eraser device, a support for a plurality of circular eraser bodies comprising a carrier plate of a length less than the combined diameters of said bodies if laid edge to edge and of a width substantially less than the diameters of said bodies, and means adjacent to each end of said plate respectively projecting from opposite faces thereof for rotatably mounting said bodies respectively upon opposite sides of said plate in planes parallel thereto and so that adjacent inner marginal portions of said bodies are in overlapping relation and outer marginal portions thereof extend freely beyond the end portions of said plate. 15 20 25

4. In an eraser device, a support for a plurality of circular eraser bodies comprising a carrier plate of a length less than the combined diameters of said bodies if laid edge to edge and of a width substantially less than the diameters of said bodies, means adjacent to each end of said plate respectively projecting from opposite faces thereof for rotatably mounting said bodies respectively upon opposite sides of said plate in planes parallel thereto and so that adjacent inner marginal portions of said bodies are in overlapping relation and outer marginal portions thereof extend freely beyond the end portions of 30 35 40 said plate, and keeper discs secured by the outer end portions of said mounting means in bracing relation to the outwardly presented faces of said eraser bodies. 45
